UNITED STATES PATENT OFFICE

2,447,788

DRAINBOARD AND TUB CONSTRUCTION

Albert P. Ball, Detroit, Mich., assignor to Briggs Manufacturing Company, Detroit, Mich., a corporation of Michigan

Application May 6, 1944, Serial No. 534,488

5 Claims. (Cl. 4—187)

1

This invention relates to a combination sink and/or laundry tray unit or the like and particularly to a structure of this kind adapted to be equipped with a removable drainboard.

An object of the invention is to provide a sink or tub unit having two spaced basins or sumps separated by a double wall partition with a laterally extending rim extending continuously around four sides of the sumps, and in which the walls of each sump are joined to the rim by an offset portion forming a step extending continuously around the unit and constructed to support a sliding drainboard, the improved construction being such that the drainboard may be positioned over either sump and when so positioned will slope toward the opposite or uncovered sump so as to drain water thereinto.

A further object of the invention is to provide an improved double basin or sump unit capable of being used as a sink or laundry tub or a combination thereof, the structure being provided with an improved sliding drainboard supported in improved manner and adapted to be positioned over either sump.

Another object of the invention is to provide a sliding or removable drainboard for a double basin or sump unit which may be supported in inclined fashion over either sump by engagement of one end with the double wall partition separating the sumps and of the opposite end with an offset step formed in the end wall of the sump, the construction being such that the drainboard may also be supported in any intermediate position.

Still a further object of the invention is to provide an improved sliding drainboard which may be supported in inclined manner for draining purposes over either sump of a double sump sink or laundry tray unit and without necessitating any alteration in the construction of the unit to enable the drainboard to be positioned and supported in this manner.

Another object of the invention is to provide a structure as above described in which the drainboard may be positioned over either sump in such manner that it will slope or be inclined in one direction or the other so as to drain water into either of the sumps as desired.

Other objects of this invention will appear in the following description and appended claims, reference being had to the accompanying drawings forming a part of this specification wherein like reference characters designate corresponding parts in the several views.

Fig. 1 is a plan view of a sink or laundry tray unit having a sliding or removable drainboard and

constructed in accordance with the present invention.

Fig. 2 is an enlarged section taken substantially through lines 2—2 of Fig. 1 looking in the direction of the arrows.

Fig. 3 is a transverse section taken substantially through lines 3—3 of Fig. 2 looking in the direction of the arrows.

Fig. 4 is an enlarged fragmentary section taken substantially through lines 4—4 of Fig. 2 looking in the direction of the arrows.

Fig. 5 is an enlarged fragmentary section taken substantially through lines 5—5 of Fig. 2 looking in the direction of the arrows.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

In the drawings there is illustrated, by way of example, one embodiment of the present invention as applied to a combination sink or laundry tray unit preferably formed from sheet steel. The sink or laundry tub unit in its final form after fabrication is provided with two spaced sumps or basins 10 and 11. In the present instance these sumps are shown as having the same depth although it will be understood that one sump may be formed deeper than the other. Each sump 10 and 11 comprises an end wall 12, front and rear side walls 13 and 14 respectively, and a bottom 15. The bottom of each sump is embossed and pierced to provide a drain opening 16. Near the upper edges of the walls 12, 13 and 14 each sump is formed with an offset portion 17 forming a step or ledge which, as illustrated in Fig. 1, extends continuously around the three sides of each of the sumps. The side walls of the sumps above the offset 17 terminate in a laterally extending generally horizontal flange or rim 18 which may be pierced to provide apertures or holes 19 for the reception of fastening devices by means of which the sink or laundry tray unit may be secured to a support in any conventional manner.

The sumps or basins 10 and 11 are separated by means of a double wall partition 20. One wall 20a of this partition forms an end wall of the sump 10 and the other wall 20b of this partition forms an end wall of the sump 11. It will be

noted that the upper end 20c of this partition terminates a distance below the plane of the continuous marginal rim flange 18, as illustrated in Fig. 2, and in the present instance the crowned top 20c of the partition extends to a point intermediate the top and bottom of the offset step 17. In view of the fact, therefore, that the top 20c of the partition extends a small distance above the bottom of the offset 17, the latter at the ends of the partition will have offset portions 17a of somewhat less depth than the depth of the offset 17. As shown in Fig. 2, the line 21 indicates substantially the bottom of the offset step 17 extending continuously around three sides of each sump and it will be seen that the curved top 20c of the double wall partition intersects this offset and at its highest point extends a small distance above the line 21 although below the plane of the marginal rim or flange 18. The top surface of the partition curves downwardly at opposite sides so as to merge smoothly into the adjoining step portions 17.

The sink or laundry tray unit is provided with a sliding drainboard 22 which may be pressed or stamped from sheet metal. The top surface of the drainboard is formed with longitudinal drain grooves 23 and the front and rear longitudinal sides of the drainboard are formed with downwardly extending parallel flanges 24 terminating in inturned flanges 24a. The ends of the drainboard are also bent down to provide depending end flanges 25 each of which is preferably shaped, as shown in Fig. 2, to conform substantially to the shape of the offset step 17. Thus, when the drainboard is positioned over the sump 10 in the manner shown in Fig. 2, the shaped end flange 25 thereof will substantially fit into the offset step 17 in the end wall 12 of the sump so as to be supported thereby. In like manner, when the drainboard is similarly positioned over the sump 11, the opposite end flange 25 will substantially fit into the offset 17 in the end wall 12 of the sump 11 so as to be supported thereby.

The bottom surface of the inturned flanges 24a may be covered by means of a non-metallic strip of material, such as rubber 26, secured to the flange in any suitable manner and serving the purpose of preventing metal to metal contact when the drainboard is shifted from one sump to the other. In like manner, the bottom inturned flanges 25a of the end flanges 25 of the drainboard may be provided with similar non-metallic strips 26, as illustrated in Fig. 2. A pair of longitudinally spaced pressed metal brackets 27 are mounted on the underside of the drainboard a suitable distance inwardly of each of the longitudinally extending side flanges 24. Each bracket 27 has a top flange 27a secured, as by spot welding, to the underside of the drainboard and also has a bottom flange 27b resting upon the inturned flange 24a and also secured thereto, as by spot welding. As illustrated in Figs. 4 and 5, the longitudinally spaced brackets 27 at each side of the drainboard carry studs 28 riveted to tapered portions 27c of the brackets so as to extend upwardly at an incline. Journalled on these studs are anti-friction rollers 29 and 29a each projecting in part through an aperture 30 in the flange 24. Each of the four rollers thus mounted at the sides of the drainboard may be formed of rubber or other suitable non-metallic material and are adapted at predetermined times to have rolling engagement with the offset step 17.

Each of the side flanges 24 is formed at opposite ends thereof with a notched or recessed portion 31 shaped to correspond substantially to the shape of the curved top 20c of the double wall partition 20. The notches or recesses are positioned equal distances from the end flanges 25 so that when the drainboard is positioned over either sump, as in the manner shown in Fig. 2, one of the notches or recesses 31 will fit over and embrace the top of the partition when the opposite end flange 25 of the drainboard fits into the offset step 17 and is supported thereby. When the drainboard is thus positioned it will be supported at one end upon the step 17 and at the opposite end on the upper edge 20c of the partition and will slope so as to drain water into the uncovered sump.

When the drainboard is in position over the sump 10, as in Fig. 2, with the end flange 25 seated on the step 17 at the end of the sink, the corresponding end of the drainboard will be elevated to the level of the rim 18 thus raising the adjacent rollers 29 off from the step 17, as shown in Fig. 4. However, with the notch 31 at the opposite end of the drainboard seated over the partition 20, the rollers 29a adjacent thereto will contact, or substantially so, the seat or ledge 17, as shown in Fig. 5. With the drainboard thus positioned the notches 31 will anchor it in position preventing unwanted displacement thereof while in use. The drainboard may, however, be shifted a short distance to the left in Fig. 2, thereby tilting the lefthand end upward with the bottom of the side flanges 24 resting on the partition 20 and at the same time lowering the opposite end of the drainboard to a point where the rollers 29 rest upon the step 17. In this position the drainboard will slope in the opposite direction from that shown in Fig. 2 and will then drain into the sump 10. In this manner the drainboard may be positioned over the same sump into which it drains.

The drainboard, as seen in the drawings, is narrower than the distance between the side walls 13 and 14 of each sump below the offset 17. However, the rollers 29 project laterally a distance sufficient to overlie the step and also extend below the upper edges of the notches 31. Hence, when either end of the drainboard is withdrawn from the end step, such end of the drainboard will drop down a small distance until the adjacent rollers rest on the step and support it. The rollers, of course, will have rolling engagement on the step so as to facilitate shifting the drainboard from one sump to the other.

It will be understood that when the drainboard is positioned over the sump 11 with the notches 31 at the righthand end thereof seated over the partition 20, the drainboard will be supported in the same manner as in Figs. 1 and 2 excepting the reverse thereof. In such case the rollers 29a will occupy the position shown in Fig. 4 and the rollers 29 will occupy the position shown in Fig. 5, and the drainboard will slope so as to drain water into the sump 10.

I claim:

1. A combination sink or laundry tray unit or the like comprising two sumps separated by a double wall partition, each sump having upright side and end walls terminating in a rim and offset below the rim to provide a step or ledge extending around the sides and end of the sump, and a drainboard adapted to be positioned to cover either sump with one end thereof resting upon the end wall step, the opposite end of the drain-

board having a notched or recessed portion to receive the upper edge of the partition at points intermediate the side wall steps or ledges and position the drainboard so as to drain into the uncovered sump.

2. A combination sink or laundry tray unit or the like comprising two sumps separated by a double wall partition, each sump having upright side and end walls terminating in a rim and offset below the rim to provide a step or ledge extending around the sides and end of the sump, and a drainboard adapted to be positioned to cover either sump with one end thereof resting upon the end wall step, the opposite end of the drainboard having a notched or recessed portion to receive the upper edge of the partition at points intermediate the side wall steps or ledges and position the drainboard so as to drain into the uncovered sump, said drainboard being narrower than the distance between the opposite side walls and means for supporting the drainboard thereon when shifted to uncover the sump.

3. A sliding drainboard for a double sump sink or laundry tray unit or the like having a double wall partition separating the sumps, comprising a drain top terminating in depending longitudinal side flanges provided adjacent opposite ends with notched or recessed portions adapted alternatively to receive and embrace the upper edge of the partition when the drainboard is positioned over one sump or the other.

4. A combination sink or laundry tray unit or the like comprising two sumps each having a marginal rim at its upper edge joined to the upright side and end walls of the sump by an offset inwardly projecting step, a double wall partition separating said sumps and having its upper edge from one end to the other extending at least to the height of said step, and a drainboard adapted to be positioned over either sump and of a length to cause one end to be supported on the partition and the opposite end to be supported on the step in the end wall of the sump, said drain-

board having means cooperating with the partition at points intermediate the side wall steps to cause the drainboard when positioned over one sump to slope toward and drain into the other sump.

5. A combination sink or laundry tray unit or the like comprising two sumps separated by a double wall partition, each sump having upright side and end walls terminating in a rim and offset below the rim to provide a step or ledge extending in the same horizontal plane around the sides and end of the sump, the upper edge of said partition from one end to the other extending at least to the height of said step or ledge, and a shiftable drainboard adapted to be positioned over either sump and of a length to rest at one end on the end wall step and at the opposite end on and extend over the upper edge of the partition, said drainboard having depending side flanges notched to embrace said partition and to cause the drainboard when positioned over one sump to slope toward the uncovered sump.
